Primary Examiner — Michelle E. Wilson*Assistant Examiner* — Caitlin A Laverty(74) *Attorney, Agent, or Firm* — Stevens Patent Law LLC; James Stevens(57) **CLAIM**

The ornamental design for a cup sleeve, as shown and described.

DESCRIPTION

FIG. 1 is a perspective view of a cup sleeve showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is an enlarged top plan view thereof;

FIG. 8 is an enlarged bottom plan view thereof;

FIG. 9 is an enlarged view of the encircled portion “9” in FIG. 1; and,

FIG. 10 is a perspective view of the cup sleeve of FIG. 1 as it would be positioned during use.

The dot-dot-dash broken lines show on the cup sleeve depict stitching, which does form a part of the claimed design.

The equal-length broken lines depict portions of the cup sleeve that form no part of the claimed design.

The dash-dot broken lines in FIG. 1 and FIG. 9 illustrate the boundaries of the enlarged view indicators and form no part of the claimed design.
